ROMAN Numerals

I	V	X	L	C	D	M
1	5	10	50	100	500	1000

Basic Combinations:

1	2	3	4	5	6	7	8	9
I	II	III	IV	V	VI	VII	VIII	IX
10	20	30	40	50	60	70	80	90
X	XX	XXX	XL	L	LX	LXX	LXXX	Xc
100	200	300	400	500	600	700	800	900
C	CC	CCC	CD	D	DC	DCC	DCCC	CM

Important Facts:

Four consecutive numerals that add up to 1000 are: I+I+I+I=4, V+X+X+X=18, and X+L+X+L=30.	Four consecutive numerals that add up to 1000 are: I+I+I+I=4, V+X+X+X=18, and X+L+X+L=30.
$I+V+X+L=4+5+10+50=70$	$V+X+L+X=5+10+50+10=75$

Converting Roman Numerals:

1	9	9	3
1000	900	90	30
M	CM	XC	III
